[57] CLAIM

The ornamental design for a snack bar or similar article, as shown or described.

DESCRIPTION

FIG. 1 is a front perspective view of a snack bar or similar article, showing my new design;

FIG. 2 is a top plan view thereof;

FIG. 3 is a front elevational view thereof;

FIG. 4 is a side elevational view taken from the right of

FIG. 3, the side opposite being a mirror image thereof;

FIG. 5 is a rear elevational view thereof with the lower portion of the snack bar being divided into compartments which extend through to the front;

FIG. 6 is a side elevational view from the left of FIG. 3
with the shelf in the extended position;

FIG. 7 is a top plan view of FIG. 6; and, the bottom is flat and unornamented.

FIG. I.

FIG.3.

FIG.4.

FIG.5.

FIG.6.

FIG.7.
